US0D1049246S

(12) **United States Design Patent** (10) **Patent No.:** **US D1,049,246 S**
(45) **Date of Patent:** **** Oct. 29, 2024**

(54) **SCOOTER**

(71) Applicant: **NEUTRON HOLDINGS, INC.**, San Francisco, CA (US)

(72) Inventors: **Jonathan Oxford**, Albany, CA (US); **Kyler Steele**, Sacramento, CA (US); **Meng Zheng**, San Francisco, CA (US); **Yueqian Jia**, San Jose, CA (US); **Suraj Shroff**, Sunnyvale, CA (US); **Yi Shi**, Kunshan (CN)

(73) Assignee: **Neutron Holdings, Inc.**, Sam Francisco (CA)

(**) Term: **15 Years**

(21) Appl. No.: **29/762,914**

(22) Filed: **Dec. 18, 2020**

(51) **LOC (14) Cl.** **12-11**

(52) **U.S. Cl.**

USPC **D21/423**
